UNITED STATES PATENT OFFICE.

CHARLES JOHN NOKE, OF STOKE-UPON-TRENT, ENGLAND, ASSIGNOR TO JOHN DEWAR & SONS, LIMITED, OF PERTH, SCOTLAND, A CORPORATION OF GREAT BRITAIN.

DESIGN FOR A JUG OR SIMILAR ARTICLE.

SPECIFICATION forming part of Design No. 36,171, dated December 16, 1902.

Application filed November 3, 1902. Serial No. 129,957. Term of patent 7 years.

To all whom it may concern:

Be it known that I, CHARLES JOHN NOKE, residing at 22 James street, Stoke-upon-Trent, England, have invented and produced 5 a new, original, and ornamental Design for Jugs or Similar Articles, of which the following is a specification, reference being had to the accompanying drawing, forming part hereof.

10 The figure of the drawing represents a side view of a jug, showing my new and original design thereon.

As shown in the drawing, the invention consists of the unitary design made the subject 15 of illustration in its aspect of shape, configuration, and ornamentation as applied to jugs or similar articles. The ornamentation consists of the figure of a male person enveloped in a long coat to which is attached a 20 cape and a turn-down collar, and the head of

said figure being surmounted by a cockade-hat. The figure carries in the left hand a lighted lantern and in the right hand, which is raised to the shoulder, a watchman's staff. In the background, against which the head 25 of the figure stands out in bold relief, is a bright cloud, and above all is a crescent moon.

Having described my invention, what I claim as new, and desire to secure by Letters Patent, is—

30 The ornamental design for a jug, or similar article, as herein shown and described.

In testimony whereof I have signed my name to this specification in the presence of two subscribing witnesses.

CHARLES JOHN NOKE.

Witnesses:

JOHN WILLIAM LATIMER,
JOHN HENRY COPESTAKE.
